UNITED STATES PATENT OFFICE

129,219

DESIGN FOR A DRESS ENSEMBLE

Emelia Wener, Chicago, Ill.

Application August 8, 1941, Serial No. 102,729

Term of patent 3½ years

To all whom it may concern:

Be it known that I, Emelia Wener, a citizen of the United States of America, residing in Chicago, county of Cook, and State of Illinois, have invented a new, original, and ornamental Design for a Dress Ensemble, of which the following is a specification, reference being had to the accompanying drawing, forming part thereof.

Fig. 1 is a front view of a dress ensemble showing my new design.

Fig. 2 is a rear view thereof.

Fig. 3 is a fragmentary front view of the dress member.

Fig. 4 is a rear view of Figure 3.

I claim:

The ornamental design for a dress ensemble, substantially as shown.

EMELIA WENER.
